UNITED STATES PATENT OFFICE.

WILLARD E. BLAKE AND RANDALL B. ANDROS, OF BOSTON, MASSACHUSETTS.

ELBOW-VALVE FOR HOT-WATER RADIATORS.

SPECIFICATION forming part of Letters Patent No. 642,199, dated January 30, 1900.

Application filed July 13, 1899. Serial No. 723,667. (No model.)

To all whom it may concern:

Be it known that we, WILLARD E. BLAKE and RANDALL B. ANDROS, citizens of the United States, residing at Boston, Suffolk county, Commonwealth of Massachusetts, have invented a new and useful Improvement 5 in Elbow-Valves for Hot-Water Radiators, of which the following is a specification.

Our invention consists in combining a 10 curved waterway with a plate or damper having an axial oscillation and with devices for operating the same and in constructing and adapting the same for said apparatus and use.

Our invention will be clearly understood 15 from the drawings, in which—

Figure 1 is an external plan. Fig. 2 is a 20 vertical section on line 2 2 of Fig. 1. Fig. 3 is a vertical section on line 3 3 of Fig. 2.

We will now describe the drawings. 25 A represents the pipe-angle, into which a connecting-pipe screws at a . Onto the part a' (shown in Fig. 1 as connected with A by a union-joint) is screwed the other connecting-pipe.

The pipe-angle A is intentionally made in the form shown in order to secure the easy 30 flow of the water by a curved surface and to avoid deposit of sediment.

B is a plate or damper of not quite the 35 diameter of the pipe-angle A, the difference being intended to admit of a continuous circulation of a sufficient amount of the water to prevent freezing. Instead of this lesser diameter of the damper the same result may 40 be secured by perforating the damper or by cutting off a small segment from the edge. The damper-plate B swings on the handle-rod b , which terminates in the spindle b' .

C is a housing or stuffing-box, which screws 45 onto the projection a^2 of the pipe-angle A and has the space c for the packing.

The handle or key for turning the damper 50 is D, having an extended shank d , so situated that it may be operated by the foot, and also 45 having the edge d' , which rides back and forth on the ledge or track a^3 of the pipe-angle A, said track having three stops at right, left, and center. The screw E fits down into the spindle b' and holds the handle D in place.

Upon the ledge or track a^3 of the pipe A are 55 placed three stops, between two of which the edge d' oscillates, according to which side of the center stop it is placed. In the position shown in Fig. 2, with the valve open, the key

D has reached the end of its swing and the 55 edge d' rests against a stop. When the valve is to be closed, the key D will be swung through one-quarter of a circle, and at that point d' will come in contact with the first stop upon the track a^3 . 60

The handle may swing in either of two directions; but it will be necessary to determine in which direction it is to swing before fastening it by the screw E.

The three stops shown at each extremity 65 and in the center of the segmental track a^3 are to control the swing of the valve B, first, as to the direction in which it shall swing, and, second, as to the extent of the swinging—namely, one-quarter turn, which either opens 70 or closes the valve. It will be seen from Fig. 1 that the valve-handle D must swing to the right and cannot swing to the left, because it is already against the center stop; but the angle-pipe might be in such position that it 75 was desirable for the handle D to swing to the left of said drawing, in which case it would be necessary to remove the handle D from the stem b' and place it so that said handle, when the valve is open, would rest 80 against the opposite side of the center stop from that which it now rests against.

The elbow or pipe-angle A is so constructed that the area of the inside diameter is equal 85 to the inside diameter of the pipe of the size which it is designed to accommodate, and so has no chamber for the accumulation of either air or sediment. It will be seen that the stuffing-box C serves the double purpose of holding the damper-rod in place and of making a tight joint. 90

Having described our invention, what we claim is—

In a hot-water-radiator valve, the combination of the angle-pipe A having the track a^3 95 and the projection a^2 , the damper-plate B constructed to admit a continuous circulation of sufficient water to prevent freezing, the rod b, b' , the handle D having the parts d, d' , properly connected with said damper-plate rod, 100 substantially as described and shown.

In witness whereof we hereunto set our hands this 10th day of July, 1899.

WILLARD E. BLAKE.
RANDALL B. ANDROS.
In presence of—
W. STANLEY CAMPBELL,
JOSEPH B. SHEA.
